UNITED STATES PATENT OFFICE

2,654,165

CARRY-TYPE SCRAPER WITH FRONT
DIGGER MOVING MEANSErich H. Lichtenberg, Milwaukee, Wis., assignor
to Koehring Company, Milwaukee, Wis., a corporation

Application August 5, 1947, Serial No. 766,320

7 Claims. (Cl. 37—126)

1

My present invention embodies certain novel improvements in the type of earth scraper and loading machine such as disclosed as to principle of construction in United States patents of Anderson No. 2,418,813 issued April 15, 1947, and of E. H. Lichtenberg and P. S. Webster No. 2,411,280 issued November 19, 1946.

In the operation of scraping and loading machines of the class set forth in the above patents there is employed the customary load or material receiving bowl equipped with a scraper and movable forwardly with the machine in the scraping operation for partly loading the bowl with the payload of material being excavated, together with a supplemental or secondary scraping means located in advance of the bowl and adapted to be diggingly engaged in the earth and caused to move rearwardly in the direction of the bowl and its scraper, whereby a tangible part of the payload to be excavated will be dug and scraped into the bowl by means of the secondary scraper.

A primary object of my present invention has been to improve scraping and loading machines of the class mentioned by providing instrumentalities for effecting a continuous digging movement of the secondary or front scraper device, while its rearward scraping movement to carry material into the bowl, is being effected.

More specifically speaking my invention involves the employment of means for causing continuous reciprocatory digging movement of the secondary scraper, in a vertical direction into and out of the earth, as said scraper is being operated to effect its secondary scraper or scraping function, working in conjunction with the scraping means which is carried by the bowl proper.

A full understanding of my invention and the merits of the construction proposed thereby will be had upon reference to the following detailed description, and to the accompanying drawings, and in the said drawings.

Figure 1 is a side elevation, partly broken away and shown in section, illustrating a scraper and loading machine embodying the essential features of my invention.

Figure 2 is a vertical sectional view taken about on the line 2—2 of Figure 1.

Figure 3 is a horizontal sectional view taken through one of the gear units connecting the secondary scraper operating shaft associated therewith, and bringing out more clearly the relation of the crankshaft which reciprocates the secondary scraper vertically, the view being fragmentary in nature.

2

Figure 4 is a vertical sectional view fragmentary in nature illustrating the idle position of the secondary scraper, prior to bringing said scraper into play for doing its work to contribute a certain portion of the payload material excavated thereby to the load to be received in the main bowl or body of the machine.

Figure 5 is a fragmentary sectional view taken on the line 5—5 of Figure 8.

Figure 6 is a longitudinal sectional view somewhat similar to Figure 1, showing the secondary scraper in its position when it closes the front open end of the bowl, and the bowl and said scraper elevated for travel movement of the scraping machine.

Figure 7 is a rear elevation of the machine.

Figure 8 is a general top plan view of my machine.

Figure 9 is a horizontal sectional view taken through the transmission mechanism from which driving affects are obtained for driving the secondary scraper forwardly and rearwardly, and for operating the traction wheels of the machine at high or low speed.

Figure 10 is a detail sectional view taken about on the line 10—10 of Figure 9, certain parts omitted.

Figure 11 is a horizontal sectional view taken through one of the gear boxes containing the beveled gears by which the secondary scraper transverse driven shaft is connected to the longitudinal driven shaft leading directly from the transverse shaft to the carriage connected to the secondary scraper.

Figure 12 is a vertical sectional view taken about on the line 12—12 of Figure 8 and showing the worm gear and worm housing with the worm engaged with said gear.

Figure 13 is a vertical longitudinal sectional view fragmentary in nature and showing the clutch means for driving the worm shaft, the worm gear engaged with the worm on said shaft and other parts that are driven from said worm gear shaft.

The drawings forming a part of my application are intended to depict one general embodiment of construction of a machine built in accordance with said invention. It is to be understood that various types of frame structures may be employed in conjunction with the improved secondary scraper operating mechanism that forms the essential feature of my present improvement.

Describing the general frame construction and wheel mounting means of my present machine I

refer particularly to Figures 1 and 8 of the drawing. In these figures the frame or chassis of the machine is denoted 1 and comprise spaced channel beams or sides connected together at their front ends by a crossbeam 2, and connected at their rear ends by a crossbar 3, there being a second crossbar 4 spaced forwardly from the bar 3 and also connecting the side members or channels of the chassis or frame 1. At opposite sides of the rear portion of the frame 1 of the machine are supported the hydraulic units comprising the vertical cylinders 5 which receive therein the piston units 6. At their lower ends the piston units 6 are provided with suitable means in the form of bearings 7 for receiving the ends of the rear axle 8, which axle carries fixed rear wheels 9, rubber mounted, said wheels constituting the traction wheels of the vehicle and being fixed to the axle 8 so that upon rotative movement of the latter the wheels will revolve.

A suitable motor or engine 10 is supported on the rear end of the chassis or frame 1 being carried directly on the crossbars 3 and 4. This engine may be an internal combustion engine or any other suitable type of motor having a driving or engine shaft 11.

The driving or engine shaft 11 of the motor 10 enters a transmission gear box 12 (see Figure 9) and operates the transmission gears in said box for transmitting the drive of the engine to the traction wheel operating shaft 13 extending from one side of said housing 12.

The transmission gearing in the housing 12 may be of any conventional type and is adapted under the control of a shift lever 14 leading upwardly from the housing 12, and the control of a second shift lever 15 connected by linkage and lever parts 16 and 16a to a shift yoke 18, to effect driving of the shaft 13 at high or low speed. The shaft 13 in turn is connected by drive chain 17 (see Figures 7 and 8), with the rear axle 8 for producing the rotation of the rear wheels 9 of my machine for traction purposes.

At the rear of my machine I provide a suitable seat 18 for the driver or operator of my scraper and adjacent to said seat I provide the steering wheel 19 connected by a rod 20, lever 21, second rod 22, second lever 23, and transverse rod 24 to the shifting link 25 which is attached to the steering arms 26 offstanding rearwardly from the front pivoted axle 27 which carries the front wheels 28 of the machine, said wheels freely rotating on said axle. The front axle 27 is directly carried or connected with the inner piston unit 29 of a hydraulic unit at the front end of the machine comprising the cylinder 30, said cylinder being fixedly mounted upon the front cross bar or member 2 of the chassis of my machine.

The purpose of the hydraulic unit 5 at the rear end of the chassis or frame 1, and the hydraulic unit 30 at the front end is to enable raising and lowering movements of the frame 1 to be produced by introducing a fluid under pressure into the cylinders 5 and 30 to act on the pistons 6 and 29 of said units 5 and 30 respectively for elevating the same relative to the wheels 9 and 28. By relieving the pressure fluid from the cylinders 5 and 30 it will be obvious that the pistons 6 and 29 respectively in said units will be permitted to move upwardly in the cylinders 5 and 30 in which they operate, thereby to lower the frame 1 relative to the wheel base of the machine, all for purposes which will be more apparent hereinafter.

Since the hydraulic units 5, 6, 29 and 30, are 75

of a known type I do not illustrate the usual provisions of conduits leading from a valve stand adjacent to the driver's seat, and which conduits under the control of the valve levers at said valve stand will affect the admission and release of pressure fluid to and from the cylinders 5 and 30 for elevating and lowering the frame 1 in relation to the wheel base, respectively. The use of such conduits and valve controls is a common expedient in this art of scraper machines and similar machines where such controls are needed so I do not illustrate these features in any detail.

I now describe the scraper features of my machine. The rear or bowl scraper which I employ may be said generally to be of a known type somewhat similar to the construction employed in the Anderson patent previously referred to. Said rear scraper comprises the bowl 31 including a bottom 32 a back and suitable sides, said bowl being open at its front end, and equipped on its bottom at the front edge of the latter with the so-called rear scraping blade 33 raised at an angle to engage into the ground for digging and scraping operation as customary in this type of machine. The bowl 31 at its sides is supported pivotally at 34 to depending frame brackets or members 35 which extend downwardly from the side channels of the frame 1. Any suitable means may be employed for rocking the bowl 31 forwardly on its pivotal supports 34 to effect a dumping action of the bowl after the well known manner. For this purpose I illustrate the use of hydraulic units 36 which units are connected at their rear ends to brackets 37 on the sides of the chassis 1, the piston parts of said units being connected at 38 to the sides of the bowl 31 so that on introducing a fluid pressure medium into the unit 36 the bowl 31 may be rocked upwardly at its rear portion for tilting dumping action of the material loaded therewith.

Arranged on the front portion of the chassis or frame 1 of my machine is a carriage which comprises a side frame member 39 arranged near each side channel member of the frame 1 and equipped with supporting wheels 40 arranged to travel in the adjacent channel portion of the chassis side frame member. Each of the carriage frame members 39 which are arranged generally vertically of the chassis or frame 1 is formed with vertical extensions 41 having horizontal openings therein, the openings of the said extension being disposed to receive loosely passing therethrough front scraper operating driven screw shafts 42.

It is noted that the frame members 39 of the frame 1 are connected together by means of cross shafts 43 so the two parts 39 operate as a unit carriage in moving longitudinally of the frame members 1.

Arranged between the extensions 41 of each of the frame members 39 is a gear box 44 through which the adjacent screw shaft 42 passes in a direction longitudinally of the side members 1 of the frame. In each gear box is arranged a beveled gear 45 which is splined to the shaft 42 (see Figure 3), and the second beveled gear 46 which meshes with the gear 45 and is mounted upon the adjacent end 47 of a crankshaft 48 which spans the space between the side frame members 1 and is carried by the two gear boxes 44 associated with the screw shafts 42, the gear boxes having suitable bearings for receiving the end portions 47 of the shaft 48.

As seen best in Figure 2, I provide, a con-

siderable distance in advance of the bowl 31 and its scraper 33 which is the primary scraper, a secondary scraper 49 which involves a substantially relatively vertical scraper blade 50 mounted at the lower end of the body of said member 49. The secondary scraper 49 is supported on the crankshaft 48 by means of a plurality of straps or loop hangers 51 that freely support the upper portion of the scraper 49 upon the cranks of said shaft 48, the latter being gear driven by means of the gears 45 and 46 previously described.

Intermediate its upper and lowermost portions the secondary scraper 49 is linkedly connected by means of the link members 52 attached at one end to brackets on the front face of the scraper 49 and having their rear ends pivotally attached to the lower end portions of the side frames 39 of the carriage previously described. In other words the secondary or front scraper 49 is mounted between the frame members 39 of the trolley or carriage that operates longitudinally of the front portion of my scraping machine.

As previously stated the shafts 42 are screw shafts and the screw portions of these shafts pass through screw threaded openings in the rear end portions of the gear housings or casings 44, and the front end portions of the latter (see Figures 3 and 5) for the detailed construction. The forward ends of the screw shafts 42 are mounted in suitable bearing members 53 on the front main cross bar 2 of the frame of my machine. The rear ends of the shafts 42 extend to gear boxes 54 supported on the side members of the frame 1 near the rear portion of the frame which gear boxes contain beveled gears 55 one on each shaft 42 and one in each box 54, the beveled gears 55 meshing with other beveled gears 56 which are carried by the ends of a transverse driven worm gear shaft 57 extending across the frame of my machine just at the rear of the material receiving bowl 31.

As shown in Figure 8, Figure 12 and Figure 13 the shaft 57 carries the worm gear 58 keyed thereto and arranged in housing 59. The gear 58 is engaged by a driven worm 60 on a worm shaft 61 which enters the clutch housing 62 adjacent to the engine 19 and the transmission gear housing 52, and the shaft 61 carries a loose beveled gear 63 meshing with the beveled gear 64 keyed to an output shaft 65 that leads into the upper rear portion of the transmission gear case 12. The said shaft 65 (see Figure 10) carries a spur gear 66 which meshes with a spur gear 67 which is a part of the traction drive gearing in the transmission case 12 said gear 67 in turn meshing with a spur gear 68 forming one of said traction transmission gears.

By operating a suitable hand lever 69 on the clutch housing 62, which lever 69 is connected by a throw rod 70 to a sliding clutch member 71 in the clutch housing 62, the loosely mounted beveled gear 63 may be clutched to the member 71 which is keyed or splined on the shaft 61, and thereby the drive of the engine shaft 11 may be transmitted (through certain of the transmission gears described in reference to Figure 9 and Figure 10, whereby to drive the shaft 65), to carry the drive of said shaft 65 to the shaft 61 which drives the cross shaft 57.

Having in view the construction of my machine as before set forth I will now describe the general operation of the machine under practical conditions of its use.

Referring particularly to Figure 1 of the drawing it will be assumed that under the power of

the traction drive to the rear wheels 9 my machine has been driven forward while the bowl 31 and its digging scraper 33 are in the position shown in Figure 1 for scraping up the undug earth as the machine advances. At a certain time in the operation of my machine in its forward or advancing movement especially under normal conditions of heavy digging, the traction effort at the wheels 9 will be insufficient to move the bowl 31 and its scraper 33 forwardly, at which time the wheels 9 will begin to spin and the bowl cannot be further filled by the traction operation. It is at this time that I bring into play the operation of my forward or secondary scraper 49 which normally occupies the position in which it is shown in Figure 4, when my machine is driven forward for the digging scraping action of the parts 31 and 33. Assuming that my machine has now come to rest due to the inability to secure sufficient traction effort at the wheels 9 to move the bowl 31 forward with its scraper 33, the operator of the machine will operate the clutch lever 69 to throw in the clutch 71 for connecting the auxiliary driving shaft 65 with the worm driving shaft 61. In this manner the screw shafts 42 will be driven clockwise, we will say, looking forwardly of the machine and their first driving effect will be to operate in the screw threaded portions of the gear housing 44 to cause these gear housings to travel rearwardly along the shafts 42, thereby to rock the scraper member on the carriage comprising the frame parts 39 so that the scraper member will assume the position substantially as shown in Figure 1 as to relatively tilted vertical arrangement. When the gear housings 44 engage the rearmost of the extensions 41 on the carrier aforesaid the abutment action will cause a rearward movement of the carriage carrying the scraper member 49 bodily with it, the wheels 40 traveling in the channels of the side members of the frame 1. This is the position in which the front scraper 49 is illustrated in Figure 1 in which it will be seen that the scraper has been moved rearwardly some distance and is engaged in the undug earth and is scraping this undug earth rearwardly to cause it to enter the bowl 31 at the front open end of the latter.

When the scraper 49 has accomplished its necessary secondary scraping operation excavating the virgin earth in advance of the scraper 33 of the bowl 31, and reaches a position in which it is substantially closing the front end of the bowl 31, (see Figure 6), the rearward movement or drive of the scraper 49 toward the bowl 31 is discontinued by operation of the lever 69. The bowl 31 has now been filled with a full payload approximately two-thirds of which we will say has been excavated by the scraper 33 and the remaining third excavated and carried into the bowl 31 by the scraper 49. Thereupon the pressure fluid supplied to the hydraulic units including the cylinders 5 and 30 is caused to operate the pistons within said units to effect an elevation of the frame which is carried by the parts 5 and 30, thus to lift the frame vertically relatively to the wheel base of the rear wheels 9 and the front wheels 28, so as to bring the parts of my machine into substantially the positions which are illustrated in Figure 6. The scrapers are now disengaged entirely from the ground, the scraper 49 acting as a closure for the elevated bowl 31, and the machine is ready now to be driven off to the place of deposit of the material. The driving off of the machine to the site where

the material is to be deposited from the bowl 31, by high speed movement of the machine as contrasted with the low speed used for digging, will be effected by operation of the transmission gearing under the control of the levers 14 and 15 previously described.

When the machine reaches the place for deposit or spreading of the material, the rotation of the shafts 42 is reversed from the previous rotation which caused the rearward movement of the front scraper 49, and in this way the front scraper 49 is moved forwardly away from the bowl 31 so that the material in the bowl may be discharged therefrom by operating the hydraulics 36 which are adapted to rock or tilt the bowl 31 into dumping position along the lines previously described, after a known method of emptying the said bowl.

At a certain period of the reverse or counter-clockwise rotation of the shafts 42 the inertia of the carriage comprising the frame members 39 and supported parts will enable the gear housings under the reverse actuation of the shafts 42 to move forwardly relatively to the carriage parts until said housings engage the front extensions 41 of the carriage members 39 whereupon the front scraper 49 will be rocked to its normal out-of-operation position as seen in Figure 4, at which time said scraper will be located near the front end of the frame 1, with its blade 50 elevated above the ground. The scraping machine having been brought back to the place of excavation and scraping, the operation of scraping for a fresh filling of the bowl 31 as above set forth will be repeated again and again until the excavating job is completed.

It is to be understood that any conventional clutch and transmission mechanisms may be employed within the purview of my invention, for the purpose of effecting the driving of the traction wheels 9 of my machine, and for the purpose of reversible operation of the driven screw shafts 42 by which the movement of the front scraper 49 is likewise controlled.

Of special importance in regard to the operation of the front scraper 49, it should be noted that when said front scraper is put into operation for movement in a generally horizontal direction, the driving operation of the screw shafts 42 will communicate driving movement through the gears 45 and 46 to the crankshaft 48. Thus it is that while the scraper 49 is moved horizontally relatively speaking and in the direction of the bowl 31 the crankshaft through its connections 51 to the body of the scraper 49 will cause a relatively high speed vertical digging reciprocatory movement of the scraper 49. Thus it will be seen that the scraper 49 will break up the earth effectively as it engages the same and pushes the earth rearwardly in a scraping manner in the direction of the open end of the bowl 31. In the vertical reciprocation and practically oscillatory movement of the front scraper 49 the links 52 move up and down so as to afford the necessary freedom of movement of the scraper 49 in a vertical direction, while said links act as compression members between the carriage frame parts 39 and the scraper 49, for forcing the scraper rearwardly as the carriage itself moves rearwardly along with the scraping blade and body parts 39 and 50. Of course when the scraper 49 is caused to move forwardly in its non-digging movement it is at the same time vibrated or reciprocated vertically at relatively high speed but being up-

raised at the elevation substantially as depicted in Figure 4 the front scraper is ineffective to do any scraping and digging work.

While any suitable transmission gear unit 12 may be availed of, that shown in Figures 9 and 10 includes certain parts additional to those previously mentioned. The output shaft 11 enters the rear side of the housing 12 and has a bevel gear 75 which meshes with loose bevel gears 76 and 77 on the short shaft 78. Shaft 78 carries fixed small spur gear 67 previously mentioned as meshing with the gear 66; also carries larger spur gear 79 fixed thereon. Bevel gears 76 and 77 turn constantly when the engine shaft 11 is operating and these gears have clutch members thereon to coact with clutch members of a double clutch sleeve 80 keyed to shaft 78. Sliding of the clutch sleeve 80 in one direction engages a clutch member thereof with that of one of the gears 76-77 to drive the shaft 78 and the shaft 65 geared thereto in one direction of rotation, which drive transmitted by shafts 61 and 57 will turn the screw shafts 42 in one direction. If the sleeve 80 is moved in an opposite direction, it will engage the other clutch member thereof with the other of the gears 76-77 and thus effect driving of the shafts 65, 61, 51, and 42 in an opposite direction to that last described, on proper use of the clutch means 69-70-71 as needed for operating shaft 61. Thus, reverse operation of shafts 42 for reverse movement of the scraper 49-50 is obtained.

The gear 79 meshes with a gear 81 and the gear 67 meshes with the gear 68 previously mentioned. Gears 81 and 68 are loose on the shaft 13 provided for traction wheel driving.

The shaft 13 in housing 12 carries a double clutch sleeve 82 operated by the shift yoke 18 and capable of clutching to either gear 81 or gear 68. Operating of the sleeves 80 and 82 in proper combination actions will enable rotation of the shaft 13 reversely, and at high or low speeds, for traction wheel driving.

As stated before, many different conventional clutch and transmission gear units may be employed in lieu of those in the housings 62 and 12, respectively.

Having thus described my invention, what I claim as new and desire to secure by Letters 50 Patent of the United States is:

1. In a scraper of the class described, in combination, a supporting frame, traction means therefor, a load carrying body on the frame comprising a bowl open at its front end, a rear digging scraper at the front bottom portion of the bowl, a front digging scraper in advance of and spaced from said rear scraper, a carriage mounted on the supporting frame for longitudinal movement, a crankshaft mounted on said carriage and having the cranks thereof connected to the front scraper for imparting a vertical digging movement to the front scraper, and means on the supporting frame for moving the front scraper horizontally thereof and simultaneously driving said crankshaft.

2. A scraper as claimed in claim 1, combined with mounting means for the crankshaft, movable relatively to the carriage and operable by the driving means for abutment with the carriage to move the latter in opposite directions on the supporting frame, and connections between the carriage and the lower portion of the front scraper.

3. In a scraper of the class described, in combination, a supporting frame, traction means

therefor, a load carrying body on the frame comprising a bowl open at its front end, a rear digging scraper at the front bottom portion of the bowl, a front digging scraper disposed in advance of and spaced from the rear scraper, driving means on the supporting frame comprising a longitudinal drive shaft and a transverse crankshaft operable from the drive shaft, connecting means between the upper portion of the front scraper and the cranks on said crankshaft, a carriage movable longitudinally of the supporting frame and operably connected with the said drive shaft, and movable relatively to the mounting means between the front scraper and the crankshaft and pivoted link connections intermediate the lower portion of the said front scraper and said carriage.

4. In a scraper of the class described, in combination, a supporting frame, traction means therefor, a load carrying body on the frame comprising a bowl open at its front end, a rear digging scraper at the front bottom portion of the bowl, a front digging scraper in advance of and spaced from the rear scraper, a carriage mounted on the supporting frame for movement longitudinally thereof and driving means for moving said carriage forwardly and rearwardly on the supporting frame, mounting means connected with the front scraper to support the same on the carriage and connected with the said driving means, said mounting means being disposed so as to abut with the carriage to shift the carriage in its forward and rearward movements on the supporting frame on operation of the driving means, said mounting means for the front scraper including instrumentalities operated automatically incident to movement of the mounting means by the driving means for imparting vertical digging reciprocatory movement to the front scraper as it moves horizontally on the supporting frame.

5. A scraper as claimed in claim 4, in which the mounting means for the front scraper includes pivot link connections between the carriage and the lower portion of the front scraper. 45

6. In a scraper of the class described, in combination, a supporting frame, traction means

therefor, a load carrying body on the frame comprising a bowl open at its front end, a rear digging scraper at the front bottom portion of the bowl, a front digging scraper in advance of and spaced from the rear scraper, mounting means on the frame for supporting the front scraper for operation at a predetermined digging depth, and means to impart horizontal scraping movement of the front scraper toward the bowl and simultaneous vertical movement of said front scraper while moving horizontally, combined with a carriage mounted on the supporting frame, independently of the said body, and connections movably mounting the front scraper on the carriage, the front scraper movement imparting means being connected to the carriage.

7. In a scraper of the class described, in combination, a supporting frame, traction means therefor, a load carrying body on the frame comprising a bowl open at its front end, a rear digging scraper at the front bottom portion of the bowl, a front digging scraper in advance of and spaced from the rear scraper, mounting means on the frame for supporting the front scraper for operation at a predetermined digging depth, and means to impart horizontal scraping movement of the front scraper toward the bowl and simultaneous vertical movement of said front scraper while moving horizontally, combined with a carriage mounted on the supporting frame, independently of the said body, and connections movably mounting the front scraper on the carriage, the front scraper movement imparting means being connected to the carriage, together with instrumentalities on the carriage operable by said movement imparting means to cause the said simultaneous vertical movements of the front scraper.

ERICH H. LICHTENBERG.
